*Primary Examiner—Ted Shooman**Assistant Examiner—Cheri Cohen**Attorney, Agent, or Firm—Oppenheimer Poms Smith***[57] CLAIM**

The ornamental design for a multipurpose golf tool, as shown and described.

DESCRIPTION

FIG. 1 is a perspective view of a multipurpose golf tool showing my new design;

FIG. 2 is an enlarged front elevational view thereof;

FIG. 3 is a left side elevational view thereof; the right side elevational view being a mirror image thereof;

FIG. 4 is a rear elevational view thereof;

FIG. 5 is a top plan view thereof;

FIG. 6 is a bottom plan view thereof; and,

FIG. 7 is a perspective view thereof showing the ball marker thereof in a removed position.
